[57] CLAIM

An ornamental design for a baking dish and lid, as shown and described.

DESCRIPTION

FIG. 1 is a front elevational view of a baking dish and lid showing my new design;

FIG. 2 is a left side elevational view thereof;

FIG. 3 is a top plan view thereof with the cover on the dish;

FIG. 4 is a cross-sectional view thereof taken along the line 4—4 of FIG. 3;

FIG. 5 is a rear elevational view thereof with the cover exploded;

FIG. 6 is a right side elevational view thereof with the cover exploded;

FIG. 7 is a front elevational view of the cover thereof;

FIG. 8 is a left side elevational view of the cover thereof;

FIG. 9 is a bottom view of the cover thereof;

FIG. 10 is a top plan view of the dish thereof without the cover; and,

FIG. 11 is a bottom view of the dish thereof with the cover on the dish.
